STEEL SMELTING FURNACE

Alfred Schack, Meerbusch, near Dusseldorf, Germany, assignor to Rekuperator Gesellschaft mit beschränkter Haftung, Dusseldorf, Germany, a body corporate of Germany

Application July 30, 1938, Serial No. 222,073
In Germany August 28, 1935

1 Claim. (Cl. 122—7)

The use of recuperators with Siemens-Martin steel smelting furnaces frequently gives rise to difficulties, as the exhaust gases from the furnace are very hot and the available recuperators 5 rapidly scorch because of the precipitation of the hot, and therefore still liquid, particles of dust contained in the exhaust gases.

The invention relates to a steel smelting furnace lay-out, in which the combustion air is heated by a recuperator that is heated by means of the exhaust gases from the smelting furnace and in which a steam boiler heated by the exhaust gases that flow to the recuperator is provided between the recuperator and the smelting furnace. The steam boiler stands according to 10 the invention in such relation to the recuperator with respect to the flow of the exhaust gases that the loss of pressure in the exhaust gases flowing through the steam boiler is only a fraction of the 15 loss of pressure in the exhaust gases flowing through the recuperator. Therefore the resistance to flow in the boiler is determined so as to be less than half the resistance to flow in the recuperator. Generally the relationship is such 20 that the resistance in the boiler amounts to only about one-tenth of the resistance in the recuperator. The determination of the resistances in accordance with the invention is based on the 25 following facts:

30 The particles of dust that are carried by the exhaust gas from the Siemens-Martin furnace are in a liquid state at temperatures between 1250° C. and about 1350° C. When these liquid particles of scale strike against heating surfaces, they solidify on the surfaces and form deposits 35 that are difficult to remove. Consequently the stream of exhaust gas that carries these liquid particles of scale must be so thoroughly cooled—as far as possible without any considerable disturbance to flow, such as without causing change 40 in direction of flow and so on—that the temperature is considerably below the melting point of the particles, for example 1100° C. Numerous and considerable changes in direction and the 45 like are factors in the flow of the gas attended by loss of pressure in the stream of exhaust gas. Hence according to the invention the boiler is made so large in its cross-sectional dimensions of passage that the resistance to flow offered to 50 the exhaust gases is only a fraction of the resistance to flow which the exhaust gases subsequently experience in the recuperator, where the temperature of the dust is considerably below the melting point and therefore the deposits of 55 dust are not objectionable.

In order to avoid in the recuperator the accumulation of the constituents of the dust that melt at a low temperature, and whose sintering point lies near to the temperature of the tubes 5 of the recuperator on the air side in accordance to the invention, when, also, use is made of a steel recuperator, raised considerably higher than is often the case in ceramic heat exchangers, regenerators as well as recuperators, 10 that is to say, to about 40 k. cal./m²h° C.

This increase in the coefficient of heat transmission can be secured in known manner by correspondingly raising the speed of flow of the air stream or by the use of members built into the 15 path of the air. In this way the temperature of the walls of the tubes is reduced and accordingly there is a cooling of the defining layer between the heating gas and the wall of the tube and consequently a reduction of the sintering point 20 of the dust. The dust can then be blown off from these tubes by compressed air or like means. In consequence of the reduction in the danger due to dust in the heating system, the possibility is thus afforded of working the steel smelting furnace with coal dust which hitherto has been difficult owing to the higher content of dust 25 in the hot exhaust gas, combined with the relatively low melting point of the dust.

A smelting furnace system constructed according to the invention is diagrammatically illustrated by way of example in the accompanying drawing in which:

Fig. 1 is an elevational view of the smelting furnace system; and

Fig. 2 is a sectional view taken on the section line 2—2 of Fig. 1.

The smelting furnace, which may be a Siemens-Martin furnace, bears the reference numeral 1. The gas discharge passage 3 which is opposite 40 to the burner openings 2 of the furnace opens into a steam boiler 4 having the water tubes 14 connecting the upper and lower drums 13, 12, as shown. The waste gases pass from the steam boiler 4 through a recuperator 5. The gases pass 45 into the recuperator 5 through the pipe 6 into the spaces between the pipes 15 and pass out at the bottom of the recuperator through the pipe 7.

The recuperator serves to heat the combustion air that is supplied to the burners. The cold air 50 is fed into the recuperator 5 at the bottom by a fan 9 through a pipe 10, which extends into the distributing part of the system of tubes of the recuperator which is impinged upon by the gases, but is not shown in the drawing. The hot air 55

passes out at the top of the recuperator through the hot air pipe 11 that is connected to the collecting member of the system of tubes of the recuperator, the pipe 11 leading to the burners 5 of the smelting furnace which are not illustrated.

I claim:

A steel smelting system comprising a smelting furnace, a fuel burner connected to said furnace, a water-tube steam generator and an air-heating recuperator, said water-tube steam generator being interposed in the direct path of flow of combustion gases from the said furnace to the said recuperator, said recuperator being connected to said furnace to supply air heated by said combustion gases for the combustion of fuel supplied to said fuel burner, the cross-sectional area

for the passage of combustion gases between the tubes of said water-tube steam generator being proportioned in relation to the corresponding free area for the passage of combustion gases in the said recuperator, so that the resistance to the flow of said combustion gases through the space spanned by the tubes of the said steam generator is less than half that of the said free area in the recuperator, whereby the said combustion gases are cooled in passage through the steam generator space so that the temperature of the molten particles in the said combustion gases is reduced below the melting point thereof, thereby avoiding corrosion on the heating surfaces of the recuperator. 5 10 15
